United States Patent Office

Des. 194,612
Patented Feb. 19, 1963

194,612

ROTARY FILE UNIT

James L. Fuller and Samuel Aston Loyd, Waynesboro,
Va., assignors to Acme Visible Records, Inc., Crozet,
Va., a corporation of Delaware

Filed Feb. 8, 1962, Ser. No. 68,728

Term of patent 14 years

(Cl. D33—7)

Fig. 2

FIG. 1 of the drawings is a perspective view of a rotary file unit showing our new design.

FIG. 2 is a top plan view thereof.

The unit is symmetrical and conveys substantially the same appearance from all sides.

We claim:

The ornamental design for a rotary file unit, substantially as shown and described.
